UNITED STATES PATENT OFFICE.

GEORGE GODDU, OF WINCHESTER, MASSACHUSETTS, ASSIGNOR TO UNITED SHOE MACHINERY CORPORATION, OF PATERSON, NEW JERSEY, A CORPORATION OF NEW JERSEY.

FASTENING-INSERTING MACHINE.

Application filed December 11, 1922. Serial No. 606,230.

To all whom it may concern:

Be it known that I, GEORGE GODDU, a citizen of the United States, and resident of Winchester, in the county of Middlesex and State of Massachusetts, have invented certain Improvements in Fastening-Inserting Machines, of which the following description, in connection with the accompanying drawings, is a specification, like reference characters on the drawings indicating like parts in the several figures.

This invention relates to machines for use in the manufacture of shoes and is illustrated herein as embodied in a machine having work supporting means arranged to support and position the work during operation thereon by the machine, and to facilitate the presentation of the work to the machine and its withdrawal therefrom.

The illustrated machine is provided with fastening inserting instrumentalities arranged to be introduced into the heel portions of shoes to insert fastenings therein, as, for example, to tack shank pieces into turn shoes. To facilitate the presentation of the work to the machine, in accordance with a feature of the invention, the illustrated work support, while the machine is at rest, remains in withdrawn position to permit the ready positioning of the work with respect to the fastening inserting instrumentalities, and when the machine is started is moved into operative, work-supporting position beneath the work, the arrangement being such that the work support reaches operative position before the moving parts of the fastening inserting instrumentalities come into engagement with the work. As illustrated, a back gage co-operates with the work support to insure the correct positioning of the work with respect to a plurality of nozzles so that the fastenings will be driven at the desired location within the shoe. It will be observed that a machine so constructed permits the operative to have free access to the nozzles in positioning the work prior to the insertion of fastenings without obstruction by the work support, but brings the work support into operative position beneath the work prior to the insertion of the fastenings and prior to the exertion of any force by the machine tending to move the work out of operative position.

While the invention is illustrated as em-

bodied in a machine particularly designed for tacking shank pieces into turn shoes, it should be understood that it is not limited to machines for this purpose but in various of its aspects is applicable to machines for performing other functions than the insertion of fastenings.

With the above and other features in view the invention will now be described in connection with the accompanying drawings and pointed out in the claims.

Fig. 1 is a side elevation of a fastening inserting machine embodying the present invention;

Fig. 2 is a plan view of a crank mechanism used in the machine of Fig. 1;

Fig. 3 is a front elevation of the head of the machine of Fig. 1;

Fig. 4 is a cross section on the line 4—4 of Fig. 3; and

Fig. 5 is a side elevation, parts being broken away to show the construction of the upper end of the driver bar, driver bar guide and certain parts associated therewith.

The illustrated machine is provided with a column 10 and a head 12, the latter having pivoted thereto as at 14 a pair of brackets 16, each carrying a set of fastening inserting instrumentalities 18. In order to adjust the two sets of fastening inserting instrumentalities toward and from each other, as may be necessary for the proper insertion of fastenings in shoes of different sizes or styles, a right and left handed screw 20 engages correspondingly threaded openings in the two brackets 16 so that by its rotation in one direction or the other it may cause their motion together or apart. A lock nut 22 is provided to clamp the two brackets 16 in adjusted position.

Slidably mounted in each of the brackets 16 is a driver bar guide 30 in the form of a sleeve housing a driver bar 32 (Figs. 1 and 5). Each driver bar guide is provided with a rack 34 meshing with a gear segment 36 pivoted at 38 to bracket 16 and arranged for oscillation, as will be more fully hereinafter described, by a link 40. At its upper end the driver bar 32 is provided with a forwardly extending lug 42 (Fig. 5) and a guide roll 44 co-operating with an appropriate surface formed upon bracket 16 to support the upper end of the driver bar during its reciprocating motion. Driver bar guide 30 carries

at its upper end an adjustably mounted cam 46 and a sleeve 48 to which is secured one end of a stiff coiled spring 50, the other end of which is operatively connected to the upper end of the driver bar as shown at 52. Fulcrumed at 54 to each bracket 16 is a lever 56 formed at the rear and between its ends with a cam surface 58 and carrying at its upper end a roll 60 arranged to co-operate with the lower surface of block 42. At its upper end lever 56 is provided with a lug 62, the rearward movement of which is limited by a stop 64. A spring pressed plunger 66 tends to rock the lever 56 rearwardly about its fulcrum 54.

During the operation of the machine and after the insertion of each fastening, gear segment 36 is rocked to lift driver bar guide 30 and with it driver bar 32. At the conclusion of the upward movement of these parts lug 42 snaps past roll 60, which then serves as a stop to lock the driver bar in raised position, the parts at this time occupying the position shown in Fig. 5. When gear segment 36 moves in the opposite direction (clockwise as viewed in Fig. 1), the driver bar guide 30 moves downwardly until the nozzle 68 carried at its lower end contacts with the work, this downward movement of the driver bar guide tensioning spring 50. When cam 46, carried by the driver bar guide 30, during the downward movement engages cam 58 carried by lever 56, it forces that lever forward so that roll 60 passes from under lug 42. The driver bar 32 then descends, being driven in its downward stroke by the force stored in spring 50.

Nozzles 68 may be supplied with fastenings by any suitable or convenient mechanism. The illustrated machine is provided with a tack pot or hopper 70 from which the tacks are fed to a pair of raceways 72. From the raceways tacks are fed by suitable separator mechanism to a pair of tubes or conduits 74 leading to nozzles 68. The separator mechanism in the illustrated machine is driven from shaft 80 (Fig. 1) through a crank disk 82, link 84, crank 86, and connecting rod 88, the latter being formed of two yieldingly connected sections and operating a gear segment 90 which, through a co-operating gear segment 92, gives an oscillating movement to an arm 94 carrying the separators. As the separating mechanism is no part of the invention claimed herein but forms a part of the subject-matter of a copending application for United States Letters Patent having Serial No. 628,234, filed March 28, 1923, by myself and Fred L. Mackenzie, as joint inventors, it is deemed unnecessary to describe it in further detail at the present time.

A work support 100 is arranged to be positioned beneath the work during the in-

sertion of fastenings. A back gage 102 carried by a suitable slide on the head 12 of the machine and arranged to be clamped in adjusted position by a hand screw 103 is located to the rear of nozzles 68 so as to facilitate the positioning of the work with respect thereto.

In order that the operative may have unobstructed access to the back gage and operating instrumentalities of the machine, the work support 100 is arranged to be held out of operative position when the machine is at rest but to be brought forward so as properly to support the work at the beginning of each cycle of operation after the machine is started and before the nozzles engage the work preparatory to the driving of the fastenings. With this in view the work support is carried at the forward end of a slide 104, the latter being provided with rack teeth 106 meshing with a gear segment 108 loose upon shaft 110. A second gear segment 112 is also loose upon the shaft 110, the two gear segments having co-operating faces shown at 114 by means of which gear segment 112 will drive gear segment 108 positively in a clockwise direction as viewed in Fig. 2. Gear segment 108 is also provided with a spring-pressed plunger 116 co-operating with a radial surface formed upon gear segment 112 so that gear segment 112 will carry gear segment 108 yieldingly in a counter clockwise direction as viewed in Fig. 2. A rack bar 118 serves to transmit power to gear segment 112, the rack bar being reciprocated by a link 120 and crank 122, the latter being rotated by mechanism hereinafter described.

Rack bar 118 also serves to transmit power to the fastening inserting instrumentalities as will now be described. A pair of ways 124 are formed upon opposite sides of rack bar 118 (Fig. 4). Each of these ways receives a roll 126, these rolls being carried by respective lugs 128 carried by slides 130 mounted in suitable ways carried by the head of the machine (Figs. 1 and 4). Each link 40 which, as described above, is operative to oscillate one of the gear segments 36 is pivoted at 132 to a lug formed upon one of the slides 130. Thus, it will be seen that the reciprocation of rack bar 118 is operative both to present and withdraw the work support and to operate the fastening inserting instrumentalities.

In order to ensure that the work support shall be in position before the nozzles 68 come into engagement with the work, gear segments 108 and 112 are of such dimensions that the work support reaches its operative position before the nozzles 68 have completed their downward movement. When the work support has reached this position further forward movement thereof is prevented by engagement of a stop 140

carried by slide 104 with a co-operating stop member 141 carried by a stationary part of the machine. When the work support reaches its operative position and can move 5 forward no further the spring plunger 116 is compressed to permit relative movement of gear segments 108 and 112 so that rack bar 118 can continue its forward movement until the nozzles come into engagement with 10 the work on the work support, immediately after which the driver bars are tripped to drive the fastenings into the work.

To permit the work support to adapt itself to the contour of different sizes and 15 styles of shoes, it is provided with a work engaging member 146 (Fig. 3) having an arcuate lower surface provided with a lug 148 positioned between co-operating spring pressed plungers 150 housed in a carrier 20 152, the latter being provided with a slot conforming to member 146 so that the latter may rock laterally in the carrier while providing a firm support for the work. Carrier 152 is provided with a downwardly extending 25 stem 154 counterbored to form a housing for a spring 156, an abutment carried by slide 104 being provided for the spring at 160. At its forward end slide 104 is provided with vertical guides 162 co-operating 30 with corresponding ways formed upon stem 154 to guide the carrier 152 in its vertical movement. From the foregoing it will be apparent that the work support is arranged to conform itself both to the thickness 35 of the work and to its contour so that the work will be firmly but not too rigidly supported during the insertion of the fastenings and will yield to prevent injury to the work by nozzle 68.

40 The machine is provided with a treadle 180 suitably pivoted at the rear to column 10 and connected by a link 182 to a two armed lever 184, 186 suitably fulcrumed upon the head of the machine. Arm 186 of 45 this lever is arranged when depressed to strike the forwardly extending arm 188 of a three armed lever fulcrumed at 190 to the head of the machine and provided with a rearwardly extending arm 192 and an upwardly extending arm 194. Anchored to the arm 194 is a spring 196 tending to rock the three armed lever is a counter-clockwise direction, as viewed in Fig. 1. Arm 192 of 50 the three armed lever is pivoted to an upwardly extending lever 198 which is urged rearwardly as viewed in Fig. 1 by a spring 200 connected at one end to lever 198 and at the other end to an arm 202 of a second three armed lever provided also with a forwardly extending arm 204 and an upwardly and rearwardly extending arm 206. A block 208 carried by link 198 contacts with 55 a block 210 carried by the forwardly extending lever arm 204 so that upward movement of lever 198 rocks three armed lever

202, 204, 206, in a counter-clockwise direction, as viewed in Fig. 1.

The machine is provided with a main drive shaft 212 receiving power from any suitable source and carrying a worm 214 70 meshing with a worm wheel 216 loose on shaft 80. Fast upon a shaft 80 is a disk 220 provided with a lug 222 in the path of movement of which is located the upper end of lever 198. Worm wheel 216 and disk 220 75 contain the co-operating parts of a hole 224 in which is mounted a pin 226 having its end portion cut away, as indicated at 228 in such a manner that when positioned as shown in Fig. 1, the worm wheel 216 and disk 218 are disconnected but when rotated through approximately 90 degrees, the worm wheel and the disk are clutched together to transmit power to the machine. Pin 226 is 80 provided with a controlling finger 230 which, when the machine is at rest, engages a block 232 carried by lever arm 206. A safety stop 233 may conveniently be provided to co-operate with a finger 234 carried by pin 226 to lock the pin in the position shown in Fig. 1 so that no power can be transmitted. During the operation of the machine this stop 233 is, of course, withdrawn from the path of finger 234. A spring 236 tends to rotate 85 pin 226 in a counter-clockwise direction, as viewed in Fig. 1, so that when lever arm 206 is rocked in a counter-clockwise direction by the upward movement of lever 198, block 232 is withdrawn from engagement with controlling finger 230 and pin 226 is rotated by spring 236 sufficiently to connect worm wheel 216 and disk 220 with the consequent operation of the machine through 90 a single cycle. Towards the conclusion of 100 the cycle, lug 222 engages the upper portion of lever 198 rocking that lever forwardly against the tension of spring 200, thus moving block 232 into position to engage controlling finger 230 so that at the conclusion of the cycle pin 226 is rotated 105 against the tension of spring 236 to disconnect worm wheel 216 and disk 220, the machine coming to rest in the position indicated in Fig. 1. Thus, it will be seen that 110 clutch mechanism is provided by means of which the machine will be caused to operate through a single cycle and then come to rest.

115 While the operation of the machine has been described in connection with the description of the machine, it may be convenient briefly to recapitulate. In utilizing the machine to tack a shank piece into a turn shoe, the shoe with the shank piece therein is 120 presented with its counter portion surrounding nozzles 68. To hold the upper of the shoe away from the nozzles a shield 250 may conveniently be provided. With the shoe thus located and with the rear part of the counter portion of the shoe positioned 125 130

against back gage 102, the operative trips the treadle, whereupon slide 118 moves forward rocking gear segments 112 and 108 so as to move the work support forward beneath the work and simultaneously lowering the nozzles into engagement with the work. The work support reaches its operative position and comes to rest beneath the heel seat portion of the sole of the shoe to be operated on before the nozzles engage the shoe, the spring of plunger 116 being compressed during the latter portion of the downward movement of the nozzles. When the nozzles reach the work or immediately thereafter, cams 46, carried by the driver bar guides which also carry the nozzles at their lower ends, contact with cams 58 rocking levers 56 in a clockwise direction, as viewed in Fig. 5, thus releasing driver bars 42 which descend and insert the fastenings. Immediately after the descent of the driver bars, slide 118 starts rearwardly, withdrawing the work support and elevating the driver bar guides, the latter carrying with them the nozzles and the driver bars.

Having described by invention, what I claim as new and desire to secure by Letters Patent of the United States is:

1. A machine for operating upon shoes having, in combination, operating instrumentalities, a work support formed and arranged to engage the heel seat portion of the sole of a shoe, and means for holding the work support out of work supporting position while the work is being positioned by the operative relatively to the operating instrumentalities and for moving the work support into supporting relation to the sole of the shoe prior to the performance of the operation.

2. A machine of the class described having, in combination, instrumentalities for operating upon the inside of a shoe, a shoe support, and mechanism operative at the commencement of each cycle of operation of the machine to move the shoe support into supporting relation beneath the sole of a shoe surrounding said operating instrumentalities, and toward the conclusion of each cycle of operation to move the shoe support away from the shoe.

3. A machine for operating upon shoes having, in combination, instrumentalities for operating upon the inside of a shoe, a back gage arranged to position a shoe relatively to said instrumentalities, a shoe support, and means for holding the shoe support out of supporting relation to the shoe to be operated upon while the shoe is positioned relatively to said back gage and said operating instrumentalities, and for moving the shoe support into supporting position beneath the sole of the shoe after the positioning of the shoe and prior to the performance of the operation.

4. A fastening inserting machine having, in combination, means for inserting fastenings in shoes, and a work support arranged for movement during each cycle of operation of the machine into and out of supporting relation to the sole of a shoe operatively positioned relatively to the fastening inserting means.

5. A machine for operating upon shoes having, in combination, a gage arranged to position the work to be operated upon, and a work support arranged for movement during each cycle of operation of the machine into and out of supporting position beneath the sole of a shoe positioned by the gage.

6. A machine of the class described having, in combination, instrumentalities for operating upon shoes, a work support having a work engaging member arranged to conform to the contour of the sole of a shoe supported thereby, and means for moving the work support into position beneath the sole of the shoe to support the shoe for operation thereon at the commencement of each cycle of operation of the machine and to move the work support from that position toward the conclusion of each cycle of operation of the machine.

7. A machine of the class described having, in combination, a work support arranged to engage the sole of a shoe and having a sole engaging member arranged for yielding movement transversely and vertically to permit the work support to conform to the contour of the sole, and means for moving the work support forward to work supporting position beneath the sole of the shoe at the commencement of each cycle of operation of the machine, and for moving the work support rearwardly from that position toward the conclusion of each cycle of operation of the machine.

8. A fastening inserting machine having, in combination, a slide, a work support carried by the slide and arranged to be positioned beneath the sole of a shoe to be operated upon, yielding means arranged to reciprocate the slide to move the work support toward operative position beneath the sole of the shoe to be operated upon, and a stop positioned to cause the work support to come to rest at a predetermined position for the performance of an operation on the shoe.

9. A machine for operating upon shoes having, in combination, instrumentalities for operating upon shoes, a work support formed and arranged to engage beneath the sole of a shoe, a slide connected to the work support, and means for reciprocating the slide constructed and arranged to move the work support yieldingly into operative position beneath the sole of the shoe at the commencement of each cycle of operation of the machine and to withdraw the work support

from operative position toward the conclusion of each cycle of operation of the machine.

10. A fastening inserting machine having in combination, a nozzle, a driver, a slide, a work support carried by the slide for reciprocating movement to and from work-supporting position, means operating at the commencement of each cycle of operation 10 of the machine to move the work support into operative relation to work previously positioned beneath the nozzle, means operating to move the nozzle into engagement with the work after the arrival of the work support in operative position, driver operating means arranged to drive a fastening through the nozzle into the work after the engagement of the nozzle with the work, means for thereafter withdrawing the driver and nozzle 20 from the work, and means for withdrawing the work support from beneath the work.

11. A machine of the class described having, in combination, a rack bar, a gear segment meshing therewith, a second gear segment, connections between the two gear segments for causing the second segment to move positively in one direction and yieldingly in the opposite direction with the first segment, a rack bar engaging the second segment, and a work support connected to the rack bar for movement thereby into and out of operative position.

12. A machine of the class described having, in combination, a work support formed and arranged to engage the heel seat surface of the sole of a shoe and means for moving the work support into and out of work supporting position tending to give the work support excess movement beyond work supporting position, a stop arranged to prevent movement of the work support beyond work supporting position, and a spring arranged to yield when the work support reaches work supporting position beneath the shoe to overcome the tendency of the operating means to give excess movement to the work support.

13. A fastening inserting machine having, in combination, a work support, means for moving the work support into and out of operative position comprising a first slide attached to the work support, a second slide, means for oscillating said second slide, a gear segment meshing with said second slide, a gear segment meshing with said first slide, a yielding connection between the two gear segments, and a stop arranged to limit the movement of the work support prior to the completion of the movement of the second slide, said yielding connection permitting relative movement of the two gear segments when movement of the work support is terminated by the stop.

14. A machine of the class described having, in combination, a work support ar-

ranged to position the heel portion of a shoe, 65 fastening inserting instrumentalities having fastening inserting devices arranged to be introduced into the heel portion of a shoe, means for moving the work support rearwardly away from the fastening inserting 70 devices to permit the presentation of a shoe to the machine while the machine is at rest, and means for moving the work support into operative relation to the work early in the 75 cycle of operation and before the insertion of fastenings when the machine is started.

15. A machine of the class described having, in combination, fastening inserting instrumentalities arranged to attach shank pieces to the heel seat portions of turn shoes, 80 a work support movable rearwardly out of the way to permit presentation of a shoe to the fastening instrumentalities while the machine is at rest, and means for moving the work support into position to support the 85 work beneath the fastening inserting means before the insertion of fastenings when the machine is started.

16. A machine for inserting fastenings in shoes having, in combination, fastening inserting instrumentalities provided with a plurality of elongated nozzles, a work support formed and arranged to engage the sole of a shoe, and mechanism operative at the commencement of each cycle of operation of 90 the machine to move the work support into position to support a shoe in operative relation to the nozzles and toward the conclusion of each cycle of operation to move the 95 shoe support away from the work.

17. A fastening inserting machine having, 100 a plurality of elongated nozzles arranged to reach into the interior of a shoe for the insertion of fastenings therein, a work support, means for holding the work support out of work supporting position to permit the operative to have unobstructed access to the nozzles while positioning a shoe relatively thereto, and means for moving the work support prior to the insertion of fastenings into work supporting position relatively to a shoe which has been brought into operative relation to the nozzles.

18. A fastening inserting machine having, 115 in combination, a plurality of elongated nozzles, a back gage arranged to position the work in operative relation thereto, a work support arranged to engage the sole of a shoe, and means for holding the work support out of operative relation to the shoe to be operated on while the shoe is being positioned for the insertion of fastenings therein, and for moving the work support into operative relation to the shoe prior to the insertion of fastenings.

In testimony whereof I have signed my name to this specification.

GEORGE GODDU.
